1 Claim 10

ABSTRACT OF THE DISCLOSURE

A method used in the drilling of hard materials, e.g. watch and clock maker's jewels, including the steps of, disposing a pair of drill-carrying spindles in coaxial oppositely-moving directions and on opposite sides of a flexible vibratable jewel-carrying blade, and drilling the jewel from its opposite sides while simultaneously vibrating the blade and jewel carried thereby.

CROSS REFERENCES TO RELATED APPLICATIONS

This is a continuation-in-part of my copending application, Ser. No. 404,292, filed Oct. 16, 1964, now abandoned.

BACKGROUND OF THE INVENTION

Field of the invention

The invention relates to a drilling method for the drilling of hard materials, such as watch and clock maker's jewels.

Description of the prior art

Known prior art includes Moses, #2,402,831 of June 25, 1946, which teaches a mechanism for the piercing of refractory bodies such as are used in the manufacture of wire drawing dies. Such mechanism allows the making of a die opening of a definite diameter through the axis of a die body.

Kurtz, #2,377,159, of May 29, 1945, teaches a method and mechanism for drilling hard substances such as diamonds. Kurtz suggests the use of opposed drill spindles.

Simons, #2,332,609, of Oct. 26, 1943, and Peters et al., #2,622,581, of Dec. 23, 1952, teach the use of drilling machines.

What the prior art references seem to lack is a teaching of the technique of using opposite drills while vibrating.

SUMMARY OF THE INVENTION

The method for the drilling consists in disposing a pair of spindles carrying drills in coaxial oppositely-moving directions and on opposite sides of a flexible vibrated jewel-carrying blade, and drilling the jewel from its opposite sides while simultaneously vibrating the blade and the jewel.

BRIEF DESCRIPTION OF THE DRAWING

FIGURE 1 is a diagrammatic sectional view of a two-spindle machine for drilling watch and clock maker's jewels according to the method of the invention;

FIGURE 2 is a sectional view of one detail of the FIG. 1 machine, drawn to a larger scale;

FIGURE 3 is a plan view of the FIG. 2 detail drawn on the same scale; and

FIGURES 4 to 8 show the drilling process as it takes place when two coaxial spindles are used, but without vibration.

2

DESCRIPTION OF THE PREFERRED EMBODIMENT

The machine includes a pair of coaxial spindles 1 and 2 which revolve in bearings 3 and 4 respectively and are driven by air turbines 5 and 6 respectively. Each spindle carries a drill 7 or 8 respectively, the two drills being coaxial as to each other and directly opposed to each other. Spindle 1 operates by gravity, while spindle 2 is subject to the action of a lever 9 pivoted at 10 and bearing a counterweight 11 which exerts on this spindle an axial force which tends to move it upwardly.

A vibrating device includes a flexible vibrating blade 12 riveted to a sleeve 13 which is fitted on a fixed shaft 14 carried by a structural part 15 of the machine frame, the sleeve being clamped on shaft 14 by a knurled nut 16. The free end of blade 12 is guided by a fixed pin 17 carried by the machine frame, there being a difference of about one tenth of a millimeter between the diameter of the hole in blade 12 through which pin 17 passes, and the diameter of the pin, to allow free movement of the end of blade 12 during the vibration thereof.

An electromagnet 18, supplied with current whose frequency can be modified as necessary, acts on vibrating blade 12 by means of a small plate 19 carried by said blade, so as to maintain the vibration of the latter.

Blade 12 bears a device, for fixing the object to be drilled thereon, which comprises a flexible clip consisting of a thin disc 20 fixed to the blade by screws 21 and cut out to provide a diametral bridge formed of two parts 20a and 20b separated by a diametral slot 22. The fixing device also comprises, at the center of disc 20, a collar 23 which is slotted diametrically so as to constitute two jaw-members 23a and 23b which are carried by the respective parts 20a and 20b of the diametral bridge and are intended to grip resiliently the object to be drilled, in this case a watch or clock maker's jewel.

The parts of the fixing device, namely disc 20, jaw-members 23a and 23b carried thereby, and a small plate 24 located beneath disc 20 between the disc and blade 12, may be readily replaced by other parts of different construction according to the form of the object to be drilled and to be held in position. For this purpose, it is sufficient first to raise upper spindle 1 and then to undo knurled nut 16 and to remove vibrating blade 12 from shaft 14.

Moreover, the vibrations permit elimination of the inner lip which otherwise would be provided in the hole, as indicated in FIGURES 4 through 8.

As a matter of fact, when drills 7 and 8 are in good condition (FIGURE 4), their end faces, designated by 7a and 8a respectively, are plane, the drilling being effected by the abrasive action of the abrasive material which is previously placed on the two faces of the jewel to be drilled, and owing to the waste of the material of the jewel which constitutes also an abrasive material.

As indicated by FIGURES 5 through 7, the more the drilling operation is carried out, the more the terminal edge of each drill as indicated by 7b and 8b respectively, is rounded, and due to the wear, so that, when the two drills engage one another (FIGURE 7), they allow between them an annular lip 25a of the material of the jewel which is designated by 25. The thicker the jewel, the more wear of the drills and the higher the inner lip. For instance, in the case of a jewel of a thickness of $2\frac{1}{2}/100$ mm. in which is drilled a hole of a diameter of $1\frac{1}{100}$ mm., the height of the lip, at its base, will be of about $\frac{1}{100}$ mm. Consequently, if the vibrating means is arranged in such a way that the amplitude of the vibrations be higher than the height of the lip, i.e. higher than $\frac{1}{100}$ mm. in the disclosed example, the vibrations eliminate the inner lip 25a.

I claim:

1. In the drilling of hard materials, the method of,

disposing a pair of spindles carrying drills disposed in co-axial oppositely-moving directions and on opposite sides of a flexible vibrated jewel-carrying blade, and drilling the jewel from its opposite sides while simultaneously vibrating the blade and jewel carried thereby.
